(57) **CLAIM**

The ornamental design for a rear module for a truck cap as shown and described.

DESCRIPTION

FIG. 1 is an upper perspective view of a rear module for a truck cap showing one embodiment of our new design;

FIG. 2 is a bottom perspective view thereof;

FIG. 3 is a first rear side view thereof;

FIG. 4 is a second rear side view thereof;

FIG. 5 is a top view thereof;

FIG. 6 is a bottom view thereof;

FIG. 7 is a first side view thereof;

FIG. 8 is a second side view thereof;

FIG. 9 is an upper perspective view of a rear module for a truck cap showing another embodiment of our new design;

FIG. 10 is a bottom perspective view thereof;

FIG. 11 is a first rear side view thereof;

FIG. 12 is a second rear side view thereof;

FIG. 13 is a top view thereof;

FIG. 14 is a bottom view thereof;

FIG. 15 is a first side view thereof; and,

FIG. 16 is a second side view thereof.

The broken lines in the drawings are included to show portions of the rear module for the truck cap that form no part of the claimed design.
